United States Patent

Des. 239,528
Patented Apr. 13, 1976

239,528

AUTOMOTIVE SERVICE CENTER

H. Stewart Thompson, St. Louis, Mo., assignor to
Eaton Corporation

Filed Sept. 6, 1974, Ser. No. 503,840

Term of patent 14 years

Int. Cl. D25—03

U.S. Cl. D13—1 B

FIG. 1 is a three quarter left front perspective view of an automotive service center showing my new design.

FIG. 2 is a left side elevation view thereof.

FIG. 3 is a right side elevation view thereof.

FIG. 4 is a front elevation view thereof as viewed from the right end of FIG. 2.

FIG. 5 is a rear elevation view thereof as viewed from the left end of FIG. 2.

FIG. 6 is a top plan view thereof on a reduced scale.

FIG. 7 is a three quarter right front perspective view thereof.

I claim:

The ornamental design for an automotive service center, substantially as shown.
